ATTORNEY

UNITED STATES PATENT OFFICE.

PAUL M. LEWIS, OF VELPEN, INDIANA.

COMBINATION FURNITURE.

1,269,102.

Specification of Letters Patent. Patented June 11, 1918.

Application filed January 5, 1917. Serial No. 140,789.

To all whom it may concern:

Be it known that I, PAUL M. LEWIS, a citizen of the United States, residing at Velpen, in the county of Pike and State of Indiana, have invented certain new and useful Improvements in Combination Furniture, of which the following is a specification.

This invention has relation to combination furniture and has for an object to provide 10 an ironing board of a novel construction permitting the same to be converted into a step ladder.

Another object of the invention is to provide an article of furniture having the above 15 named characteristics and including an arrangement whereby when the board structure may serve to provide an auxiliary platform at the upper end of the step ladder for supporting articles.

20 A still further object of the invention is to provide an article of combination furniture which will be strong and durable and which will give satisfactory service either in the capacity of an ironing board or a step 25 ladder.

In addition to the foregoing my invention comprehends improvements in the details of construction and arrangement of parts to be hereinafter more fully described and par- 30 ticularly set forth in the appended claims.

In the accompanying drawings in which similar and corresponding parts are designated by the same characters of reference throughout the several views in which they 35 appear:

Figure 1, is a view in side elevation of an article of furniture constructed after the manner of my invention, and illustrating its use as a step ladder.

40 Fig. 2, is a view of the same in front elevation, and

Fig. 3, is a view in side elevation of the same illustrating its use as an ironing board.

With reference to the drawings and par- 45 ticularly Fig. 1 thereof, 10 indicates the vertically disposed side pieces of a step ladder, and 11 the horizontal rungs or steps connecting the same after the usual manner of ladders of this type. In place of the usual

50 props for supporting said side members, I provide a support 12, hingedly connected at its upper end to the upper end of the side pieces and adapted to be disposed in down- wardly diverging relation therefrom where-

55 by the ladder may be maintained in an up-

right position. The downwardly tapering board 12 serves as a prop or as an ironing board. To retain the support 12 and side pieces 10 in fixed relation, I provide a combination brace and ironing board support 60 which is formed in sections and comprises side pieces 13 rigidly secured by rivets or the like 14 at one end to the inner side of the side pieces 10 of the ladder, said pieces 13 extending toward the support 12 and at 65 substantially right angles to the side pieces 10. The opposite ends of the sections 13 ex- 70 tend to a point substantially midway be- 75 tween the members 10 and 12 and connected to the said ends of the member 13 are a pair of sections 15. Said members 15 and 13 are connected together through the medium of hinges 16 and the opposite ends of the mem- bers 15 are provided with loops 17 which en- 80 circle guide rods 18 secured at their opposite ends to the under side of the ironing board and support 12 whereby said rods are dis- 85 posed in spaced relation from said support. The rods 18 may be bent outward at their upper ends as indicated at 19 whereby when 80 the article of furniture is to be folded, for instance by moving the members 10 and 12 toward each other and breaking the joint of the members 13 and 15, the loop 17 may be permitted to slide along the rod 18 and find 85 a resting place in the looped portion 19 whereby the ladder will be retained in a folded position. After the usual manner the upper ends of the side pieces 10 of the step 90 ladder are connected through the medium of a platform 20 which may form also an addi- 95 tional step.

To the ends of the brace members 13 which are rigidly connected to the side pieces 10 of the step ladder, I hingedly con- 95 nect the ends of sections 21 which when the article of furniture is used as a step ladder are designed to depend as set forth in Fig. 1. These sections 21 do not perform any function in this capacity of the article but 100 are nevertheless disposed out of the way.

When the article of furniture is to be used in the capacity of an ironing board, the device is turned so as to dispose the support 12 in a horizontal position. Before 105 doing this however, the above mentioned sections 21 are rotated so as to bring them in alinement with the sections 13 and 15, and the outer ends of the said members 21 may then contact with the floor and form 110

a support for the ironing board in addition to the support afforded by the side pieces 10 of the step ladder. Thus, the side pieces 10 and the supports formed by the aligned 5 sections 13, 15 and 21, are disposed in crossed relation and form a rigid support for the ironing board 12. Hingedly secured to the upper edge of the ironing board 12, is an ironing board extension 22 of a width 10 corresponding to the width of the ironing board and having edges in alinement therewith. When the device is used as an ironing board, the extension 22 is disposed in a horizontal position and in alinement with the 15 ironing board, and to retain said extension in such position a member 23 is rigidly secured to said extension adjacent its point of connection to the ironing board and is adapted to bear against the platform 20 20 of the step ladder. In this way the extension 22 is supported. It is to be noted in this connection also that when the article of furniture is used as a step ladder the extension 22 is rotated to dispose the same 25 in contact with the ironing board, whereupon the member 23 thereof will be disposed horizontally and in alinement with the top 20 of the step ladder thereby forming an additional support for articles, such 30 as a paint bucket, tools or the like.

Thus it will be seen that I have provided a novel article of combination furniture which is especially constructed so as to be durable either when used as a step ladder 35 or as an ironing board support.

The article furthermore comprises few parts and may be economically manufactured.

While I have illustrated and described 40 my invention with some degree of particularity, I realize that in practice various alterations thereover may be made and I therefore reserve the right and privilege of changing the form of the details of con-

struction or otherwise altering the arrangement of the parts without departing from the spirit of the invention or the scope of the appended claims.

Having thus described my invention, what I claim as new and desire to secure 50 by Letters Patent is:

1. An article of combination furniture including a ladder having a platform at one end, a prop for said ladder in the form of an ironing board hingedly connected to the 55 platform end of the ladder, an extension hingedly connected to the hinged end of the prop, a member rigidly secured to said extension at an angle thereto to be disposed in alinement with the platform to form a 60 continuation thereof when the article is used as a ladder, said extension being movable into a position in alinement with the ironing board with the member in contact with the platform to form a support for said 65 extension when the article is used as an ironing board.

2. An article of combination furniture including a ladder, a platform at one end, a prop hingedly connected to the platform 70 end of the ladder in the form of an ironing board, an extension hingedly connected to the hinged end of said prop, a member rigidly connected to said extension to be disposed in alinement with the platform, 75 a pair of braces formed of hingedly connected sections for disposing the prop and ladder in angular relation, and a supporting element hingedly connected to each brace for use, in conjunction with the ladder to 80 support the prop in a horizontal position when using the article as an ironing board.

In testimony whereof I affix my signature in presence of two witness:

PAUL M. LEWIS.
